UNITED STATES PATENT OFFICE.

WILLIAM OTTAWAY, OF AURORA, ILLINOIS, ASSIGNOR TO THE AURORA AUTOMATIC MACHINERY COMPANY, OF AURORA, ILLINOIS, A CORPORATION OF ILLINOIS.

EXPLOSIVE-ENGINE.

1,017,993.

Specification of Letters Patent. Patented Feb. 20, 1912.

Application filed April 13, 1910. Serial No. 555,134.

To all whom it may concern:

Be it known that I, WILLIAM OTTAWAY, a citizen of the United States, and a resident of Aurora, in the county of Kane and State of Illinois, have invented certain new and useful Improvements in Explosive-Engines; and I do hereby declare that the following is a full, clear, and exact description thereof, reference being had to the accompanying drawings, and to the letters of reference marked thereon, which form a part of this specification.

This invention relates to an improvement in explosive engines and consists in the matters hereinafter described and more particularly pointed out in the appended claims.

In the drawings:—Figure 1 is a longitudinal section through the cylinder of an explosive engine provided with my improvement, the section being in a plane passing through the central axes of the exhaust and intake valves, and the central axis of the cylinder. Fig. 2 is a cross-section through Fig. 1 on the line 2—2 thereof. Fig. 3 is a partial section through Fig. 1 on the line 3—3 thereof. Fig. 4 is a perspective view of the adjusting sleeve secured to the end of the inlet valve stem. Fig. 5 is a perspective view of the collar for the inlet valve stem. Fig. 6 is a perspective view of the sleeve secured to the end of the exhaust valve stem. Fig. 7 is a perspective view of the collar for the exhaust valve stem.

In the drawings A represents the cylinder; B, the piston; B¹, the connecting rod pivotally connected to the piston by means of a pin b; C, the explosion chamber; D, the inlet valve dome; E, the inlet valve, and F, the exhaust valve.

F¹ represents the exhaust valve stem and f the exhaust valve seat.

J is the reciprocating lifting rod which actuates the exhaust valve.

The lower end of the valve stem is threaded, as indicated at F².

G indicates a sleeve provided with a head g at one end and at its opposite end with a threaded recess g¹ to receive the threaded end F² of the valve stem. Said sleeve is split longitudinally, as indicated at g², from its upper end to points near the head. The outer surface of the sleeve body 55 is tapered, as shown at g³.

H indicates a collar provided with a tapered recess h¹ to fit the tapered body of the sleeve. This collar has an annular flange h against which bears a coil spring I which normally holds the exhaust valve in engagement with the seat. The other end of said spring engages an annular flanged ring h² which is rigidly mounted on the valve stem guide-ring F³. The collar H clamps the longitudinally split sections of the sleeve upon the threads of the valve stem and thereby holds the sleeve from turning on said stem. The valve-actuating spring I exerts constant pressure on the collar, tending to force it toward the lower or larger end of the tapered split sleeve, and thereby maintains the sleeve in clamping engagement with the screw-threaded end of the valve stem. This construction provides, in the case of the exhaust valve, a simple and reliable device for adjusting the position relatively to the valve disk, of the part which is acted on by the lifting rod J, as required for regulating the lift of the valve from its seat. Such adjustment is effected by lifting the collar H a sufficient distance to release the split parts of the tapered sleeve G from their clamping engagement with the valve stem and then turning the said sleeve to move it up or down on the screw-threaded end of the valve stem, until the lower end of the sleeve is brought into the desired vertical position with relation to the lifting rod J. When the collar H is again allowed to seat itself on the tapered outer surface of the split sleeve, it acts to clamp and hold the split parts of the same immovably upon the stem. The constant pressure of the spring on the collar always tends to tighten the parts, or to hold them firmly in contact with each other, so that there will be no liability of the same becoming loose, or the adjustment of the valve stem being changed, by the jarring of the parts occurring in the operation of the engine. A similar construction is used for adjusting the opening of the inlet valve.

E¹ is the inlet valve stem and e a guide ring in which said valve stem slides.

K is a tapered, internally threaded sleeve split longitudinally at K² and K¹ is a collar provided with a tapered recess K³ within which the tapered sleeve fits. Said collar is provided with an annular shoulder k in

which is formed an annular recess k^1 to receive the upper end of a coiled spring L which normally holds the intake valve in closed position against its seat. The lower end of said spring bears against a shoulder l formed in the guide ring e .

When the inlet valve is opened it moves away from its seat until the lower end of the collar K^1 strikes the upper end of the guide ring e . It is thus apparent, that the position of the collar K^1 on the valve stem and of the sleeve K on the stem, which determines that position, limits the opening of the valve. By withdrawing the collar and adjusting the sleeve K up or down on the valve stem, the amount of the opening of the valve may be adjusted. The sleeve K is preferably provided with diametrically opposed flat parts k^2 near its upper end for turning it by means of a wrench. The head of the sleeve G is made hexagonal, as shown at g^4 , for the same purpose.

The construction described is quite simple and at the same time provides for the ready adjustment of the valve opening, both intake and exhaust. In addition the parts are locked in their adjusted positions without the use of pins and holes in the collar or valve stem which tend to weaken them.

It will be noted that in case of the exhaust valve, the split sleeve constitutes an adjustable part which is acted on by the valve actuating means and controls the extent of lift of the valve while in the case of the intake-valve the collar constitutes an adjustable part which by its contact with a fixed stop likewise limits the lift of the valve. It is to be understood, however, that the novel construction described might be applied in a construction wherein neither said sleeve or collar comes in contact with any other

part in which case the sleeve and collar will merely act to take the pressure or thrust of a spring and transmit the same to a valve stem or any other like member. The term valve-stem, as used in the appended claims, may therefore be understood to cover any rod which is subject to the pressure of a spring exerted endwise thereon.

I claim as my invention:—

1. The combination with a valve-stem, of a sleeve surrounding and having screw-threaded connection with the stem, said sleeve having a smooth, tapered external surface and being split longitudinally in its tapered part, a collar fitting upon the tapered exterior of the sleeve, and a spring acting on said collar in a direction to force the same upon the tapered sleeve and to thereby hold the said sleeve in clamping engagement with the stem.

2. The combination with a valve-stem or like part, and a coiled actuating spring which surrounds the same, of a sleeve which surrounds and has screw-threaded engagement with the stem, said sleeve having a part which is longitudinally split, and a smooth, tapered external surface on its split portion, a collar provided with a tapered bore adapted to fit upon the tapered surface of said sleeve, said spring acting on the said collar to force the same upon the tapered sleeve and to thereby clamp the sleeve upon the stem.

In testimony, that I, claim the foregoing as my invention I affix my signature in the presence of two witnesses, this 4th day of April A. D. 1910.

WILLIAM OTTAWAY.
